UNITED STATES PATENT OFFICE.

ALBERT A. HENZI, OF CHICAGO, ILLINOIS, ASSIGNOR TO GOSS PRINTING PRESS COMPANY, A CORPORATION OF ILLINOIS.

MACHINE FOR OPERATING UPON STEREOTYPE PRINTING PLATES.

Application filed September 3, 1920. Serial No. 407,987.

To all whom it may concern:

Be it known that I, ALBERT A. HENZI, a citizen of the United States, residing in Chicago, in the county of Cook and State 5 of Illinois, have invented certain new and useful Improvements in Machines for Operating upon Stereotype Printing Plates, of which the following is a specification.

The invention relates to machines for operating upon stereotype printing plates, and more particularly to machines for taking a plate from a drag or other plate holding means of a plate casting machine, or from some other source of plate supply, and 15 conveying it to trimming mechanism and then trimming the plate.

Objects and advantages of the invention will be set forth in part hereinafter and in part will be obvious herefrom, or may be learned by practice with the invention; the same being realized and attained through and by means of the instrumentalities and combinations set forth in the appended 20 claims.

25 The invention consists in the novel parts, constructions, arrangements, combinations and improvements herein shown and described.

The accompanying drawings, referred to 30 herein and constituting a part hereof, illustrate one embodiment of the invention, and together with the description, serve to explain the principles of the invention.

Of the drawings:

35 Fig. 1 is a side elevation of the machine, looking at Fig. 2 from the left, and showing in outline the position of the plate casting machine or other plate supplying means;

40 Fig. 2 is an end elevation looking at Fig. 1 from the right, and showing the motor and drive in outline in front of the machine;

45 Fig. 3 is a horizontal section, looking downwardly and taken on the line 3—3 of Fig. 1;

Fig. 4 is a horizontal section, looking downwardly and taken on the line 4—4 of Fig. 1;

50 Fig. 5 is a vertical transverse section, taken on the line 5—5 of Fig. 1, looking in the direction of the arrows;

Fig. 6 is a vertical transverse section taken on the line 6—6 of Fig. 1, looking in the direction of the arrows;

Fig. 7 is a horizontal fragmentary detail 55 section, on an enlarged scale, taken on the line 7—7 of Fig. 5, looking in the direction of the arrows;

Fig. 8 is a side elevation, similar to Fig. 1, but showing also a plate-casting machine, 60 and the position of the mechanism during the operation of removing a stereotype plate from the drag of the casting machine,

Figs. 9, 10, 11 and 12 are diagrammatic views illustrating different stages or 65 positions in the removal of the plate from the casting machine; and

Fig. 13 is a vertical section through the plate trimming mechanism.

The machine of the present invention 70 takes the cast stereotype plates from the drag or concave member of a plate casting machine, or other suitable source of plate supply, and conveys the plate to a trimming mechanism, which mechanism trims the 75 curved edges of the plate and cuts off the tail or riser from the plate.

In the embodied machine a carrier travels to and from the trimming machine and picks up the plate and brings it to the 80 trimming station. Further as embodied the carrier engages the plate as it lies in position as cast in a casting machine and conveys it to the trimmer. The carrier preferably engages with the concave side of the 85 plate and also preferably continues to hold it during the trimming operation.

The machine is automatic in operation so far as handling and trimming the plate is concerned, but certain of the mechanisms of 90 the machine are preferably started into operation by manual means or other means actuated by the attendant.

The machine of the present embodiment 95 comprises a cylindrically shaped or hemi-cylindrical plate carrier mounted on a shaft, which shaft has a longitudinal movement whereby the plate carrier is positioned above the cast plate as it lies in the drag or concave of the casting machine.

When the plate carrier is so positioned, the shaft rotates, making one revolution, whereby the hemi-cylindrical carrier passes within and fits against the concave side of the stereotype plate, and a stop in the straight edge of the carrier engages the straight edge of the stereotype plate. As 105 the revolution of the carrier about its shaft

continues, the plate now fitting over the carrier is moved out of its place in the casting box and is brought to a stop, by the arrest of the rotating shaft, with its concave side downward and resting upon the carrier.

In said embodiment, the shaft of the plate carrier now moves longitudinally backward without rotation, thereby bringing the plate 10 into position in the trimming mechanism. In this position the plate and its carrier is rotated about its shaft, the plate thereby being carried past rotary trimming saws, the curved edges being thereby trimmed and the 15 riser cut off.

Mechanisms are provided, in said embodiment, for causing the shaft with its plate carrier, to travel to and fro without rotation, to rotate the shaft and carrier together, and for rotating the plate carrier about its shaft, for the purposes stated, together with mechanisms for timing or synchronizing the aforesaid mechanisms.

Other features of the invention, in addition 25 to the foregoing will be described in connection with the description of the details of the present embodiment. It will be understood also that all said features may be used in cooperation or certain features may 30 be employed without the others.

Referring now to the details of construction of the embodiment of the invention shown by way of example in the accompanying drawings, suitable driving means are 35 provided, such as a motor 1 having a pulley 3 mounted upon the motor shaft 2. A belt 4 runs over pulley 3, and over a pulley 5, fixed on the power shaft 6 of the machine. It will be understood that any other suitable 40 form of driving mechanism may be provided. Shaft 6 extends longitudinally of the machine, and is journaled in bearings 7, 8, 9, 10 and 11, formed on the machine frame.

Referring now in detail to the embodied 45 form of means for taking or receiving a stereotype plate from a suitable supply station or source of supply, such as the cast plate in the drag of a casting machine, and conveying it into the trimming machine, preparatory to trimming, a worm 15 is fixed 50 on shaft 6, and meshing therewith is a worm wheel 16, which is fixed on a shaft 17, the shaft being journaled in bearings 18 and 19 on the machine frame.

Mounted on shaft 17 is a reversible drive mechanism, and as embodied a double-jawed clutch member 20 is mounted to slide on shaft 17 and connected by a feather 21 to rotate with the shaft. At one side of clutch 60 member 20 is a bevel gear 22, loosely mounted on shaft 17 and having a clutch jaw 23 with which a jaw of clutch member 20 may be slid into engagement to drive the mechanism in one direction.

65 On the opposite side of the clutch member

20 are similar means for driving the mechanism in the opposite direction, said means comprising a bevel gear 24, loose on shaft 17 and having a clutch jaw 25 with which the other jaw of clutch member 20 is adapted to engage, to drive the mechanism in the opposite direction. In mesh with both bevel gears 22 and 24 is a bevel gear 30, fixed on a shaft 31, which shaft is journaled at 32 and 33 in the machine frame. Fixed on shaft 75 31 is a gear wheel 34, which meshes with a gear wheel 35. Gear wheel 35 is fixed on a sleeve 36, which sleeve is rotatably journaled in a bearing 37 on the machine frame. Sleeve 36 is provided with a shoulder 38, which together with the gear wheel 35, holds the sleeve 36 against longitudinal movement with respect to its bearing. The sleeve 36 is internally longitudinally apertured, and this aperture is provided with screw-threads 80 39. Within the aperture in sleeve 36 is a shaft 44 having a portion of its exterior provided with a screw-thread 45, which meshes with the internal threads 39 of the sleeve 36.

In the present embodied form, shaft 44 has longitudinal movement to convey or travel the plate carrier to the drag of the casting machine or other plate supplying source, and to bring the plate back to the 95 trimming machine. As embodied, means are provided for preventing rotation of the shaft 44, and consequently as sleeve 36 is rotated, the engagement of its screw-thread 39 with the screw-thread 45 of the shaft 44 imparts 100 to the shaft the necessary longitudinal travel.

In said embodiment, in order to longitudinally travel shaft 44 first in one direction to get the plate and then in the other direction 105 to bring the plate to the trimming mechanism, the direction or rotation of sleeve 36 is reversed. The embodied form of such reversing means comprises a gear wheel 46 fixed on a shaft 47, which shaft is journaled 110 in the machine frame, and fixed on shaft 47 is a worm 48, meshing with a worm wheel 49. Worm wheel 49 is fixed on a shaft 50, which is journaled at 51 and 52 in the machine frame.

Fixed to worm wheel 49 is a direction controlling and motion stopping mechanism, which operates the reversing clutch member 20 already described. The embodied form of such mechanism comprises a drum 53 120 fixed directly to worm wheel 49 or to shaft 50. Clutch member 20 is provided with a collared groove 54, in which groove works a pin or roller 55 carried on a lever 56. Lever 56 is fixed to a shaft 57, journaled in and extending longitudinally of the machine frame, and the opposite end of lever 56 is provided with a finger or roller 58, which cooperates with devices on drum 53 to swing lever 56 in one direction or the other to op- 125 130

erate and control the clutch mechanism 20, and thereby reverse the direction of rotation of collar 36.

Formed on the surface of drum 53 is a cam 63, and projecting from the drum 53 is a pin 64. Mounted on the machine frame adjacent to drum 53 is a pivoted detent hook 65, having a hub 66, which is pivoted on a shaft 67 supported on the machine frame.

Fixed to hook 65 is a lug 68, with which lug the pin 64 on drum 53 during the rotation of the drum is adapted to engage, to operate hook 65 as hereinafter described. Suitable limiting means for the hook 65 may be provided, the same being shown as a tail 69 extending from the hub 66, and adapted to engage with a pin 70 fixed in the machine frame. A spring 71 is in tension between the tail 69 and some point on the machine frame 20 to yieldingly hold hook 65 to position.

Slidably mounted in the machine frame is a rod 75, one end thereof being pivoted at 76 to the lever 56. Fixed on rod 75 is a collar 77, and in compression between this collar and the machine frame is a spring 78, which impels the lower end of lever 56 to the left in Fig. 5. Shaft 57 extends along the machine, and is provided at different points therealong, with two manual operating levers 79, as shown in Figs. 1 and 5.

The manner of operation of the mechanism just described is substantially as follows:

The operation of the mechanism for traveling shaft 44 to and fro longitudinally will first be described.

When drum 53 is in the position of Figs. 5 and 7, clutch member 20 is in neutral position, that is, out of engagement with the clutch jaws on both bevel gears 22 and 24. When the hand lever 79 is pushed downwardly in Fig. 5, the lower end of lever 56 is swung to the right in Fig. 5 against the pressure of spring 78, and is caught by hook 65. This movement of lever 56 throws clutch member 20 into engagement with the clutch jaw of bevel gear 22, and through the mechanism described, sleeve 36 is rotated in the direction to longitudinally advance shaft 44 in the direction of the plate casting machine or other source of plate supply.

Due to the rotation of drum 53, pin 64 at the proper time strikes lug 68, thereby rocking hook 65, and thus releasing the lower end of lever 56. Under the impulsion of spring 78 the lower end of lever 56 is swung to the left in Fig. 5, but owing to cam 63 being now out of the path of the lever, it passes to the extreme left end of its travel, thereby throwing clutch 20 into engagement with the clutch jaw of bevel gear 24. This, through the gear connections described, causes sleeve 36 to rotate in the opposite direction, and shaft 44 is longitudinally traveled in the reverse direction from

that previously described. In the meantime the mechanism on shaft 44 has secured the plate which is to be trimmed and brings it back into the trimming machine on this return longitudinal movement. The operation 70 and the mechanism involved in the foregoing will be later described.

When clutch member 20 is shifted by lever 56, as just described, drum 53 is also reversed, and thereafter during its rotation cam 63 comes into engagement with the lower end of lever 56 and throws it to the right in Fig. 5, against the pressure of spring 78. The mechanism is so constructed and timed that the clutch will be thrown out 80 just as the desired length of return longitudinal travel of the shaft 44 is completed. Cam 63 moves lever 56 and clutch member 20 to the neutral or disconnected position, as shown in Fig. 5, bringing the mechanism 85 to rest.

Referring now to the mechanism, connected to and cooperating with the mechanism already described, for taking the plate from the drag of the casting machine or other 90 plate supply source or station, in the embodied form this is effected by imparting rotational movement to the shaft 44 and a plate carrier which is mounted on the end 95 thereof.

In the embodied form of such means there are also incorporated devices for causing and preventing such rotational movement, and for synchronizing the longitudinal and rotational movement of shaft 44. As embodied, a sleeve 80 is rotatably mounted in 100 a bearing 81 on the machine frame, and shaft 44 passes through sleeve 80, and they are connected by a feather 82 to rotate together, while the shaft is free to slide or 105 travel longitudinally relatively to the sleeve 80. The feather 82 works in a longitudinally disposed way or slot 83 formed in the shaft 44. Sleeve 80 is shouldered at 84 to hold it in position in its bearing upon the 110 machine frame.

During the longitudinal travel of shaft 44 sleeve 80 is at rest, but when it is desired to rotate shaft 44 to take the cast plate preparatory to conveying it to the trimming 115 mechanism or station, sleeve 80 is rotated, and by reason of the connection between the sleeve and shaft 44, the shaft rotates therewith.

Referring to the embodied form of means 120 for rotating and controlling sleeve 80, a clutch member 85 is provided, mounted loosely on the shaft 44, and having at one end thereof a clutch jaw 86 connecting with the sleeve 36, whereby clutch member 85 125 may be slid to and fro along the shaft 44, but will maintain its connection with sleeve 36 to be rotated thereby. On the opposite end of clutch member 85 are formed saw-teeth or one-way clutch teeth 87. Formed 130

in the adjacent face of the sleeve 80 are corresponding clutch teeth 88. Thus member 85 will rotate in both directions with sleeve 36 but will rotate sleeve 80 only in one direction.

Means are provided for sliding or moving clutch member 85 to and fro along shaft 44 into and out of engagement with sleeve 80, so that at the proper time in the operation of the machine rotary motion may be imparted from sleeve 36 to sleeve 80 and thereby to shaft 44, or so that shaft 44 will have longitudinal movement only.

In the embodied form of such means, clutch member 85 is provided with an exterior annular groove 89 into which project fingers or rollers 90 and 91, mounted in a yoke 92 which straddles the member 85. Yoke 92 is fixed on a longitudinally slideable rod, which rod is mounted in bearings 94 and 95 fixed on the machine frame. The right hand end (in Fig. 1) of rod 93 is bent downwardly at 96 so as to be in the path of a collar 97 fixed on shaft 44. Coiled about rod 93, between the bearing 94 and the yoke 92 is a spring 98, which is in compression and impels rod 93 to the right in Fig. 1 and impels clutch member 85 to the disengaged position.

The manner of operation of the mechanism just described is substantially as follows:

During the rotation of the sleeve 36 while shaft 44 is moving to the left in Figs. 1, 3 and 8, clutch member 85 is out of engagement with sleeve 80. As shaft 44 approaches the end of its longitudinal movement to the left in said figures, collar 97 engages the end 96 of rod 93, thereby moving the rod to the left and engaging clutch member 85 with the sleeve 80.

Sleeve 80 then rotates with sleeve 36, and thereby shaft 44 ceases to advance, (because of the rotation of sleeve 80 to which the shaft is splined) but rotates with the mechanism just described. During this rotation the cast plate is taken up by mechanism and in a manner to be later described. In this operation shaft 44 makes one complete rotation. It will be recalled that just at this time the reversing mechanism, comprising reversible clutch member 20 and the controlling drum 58, operate to reverse the direction of rotation of sleeve 36. When sleeve 36 begins to rotate in the opposite direction, clutch teeth 87 are forced out of the teeth 88, and sleeve 80 stops rotating. Immediately shaft 44 stops rotating and begins its travel to the right in Figs. 1, 3 and 8. Collar 97 moves away from rod 96, and spring 98 completes the dis-engaging movement of the clutch member 85.

The embodied form of means for taking the cast stereotype plate from the casting machine, or other source of plate supply

comprises a saddle 105, preferably of part-cylindrical or hemi-cylindrical form, and preferably of a width and length substantially equal to that of the stereotype plate. The saddle 105 is shown in the plate transferring position in Figs. 1 and 8. The saddle 105 is supported on the end of shaft 44 by connections which hold them in fixed relation while traveling longitudinally to and fro and while rotating together to take the plate at the plate supplying station, but which permit rotation of the plate carrier relatively to the shaft at the trimming mechanism.

The embodied form of means for trimming the plate comprises beveled rotary trimming saws, which trim any waste metal from the head of the plate, and cut off the tail or riser at the opposite end of the plate.

Means are provided for clamping the plate upon the saddle 105, and also connections, as just stated, whereby saddle 105 with the plate thereon may be rotated in this position independently of the shaft 44. As em-

bodyed, shaft 44 is provided at its forward end with a clutch jaw member 107 fixed upon the shaft. The supporting post 106 of the plate carrier 105 has its hub 108 encircling a reduced portion 109 of shaft 44, and has a clutch jaw 110 formed thereon. The hub 108 is longitudinally slideable on the part 109 of shaft 44 to permit the clutch jaws 107 and 110 to pass into and out of mesh.

The clutch jaws are engaged during the longitudinal travel of shaft 44 and also during its rotary movement in taking the cast plate, and the clutch jaws are disengaged to permit the saddle and plate to rotate at the trimming station without rotating shaft 44. In the embodied form of said means, a spring 111 is coiled under tension

between washers 112 and 113, washer 113 being held in place by nut 114 screw-threaded on the end of shaft 109. Spring 111 thus impels the clutch jaws 107 and 110 into engagement. A stop 150 moves hub 108 to disengage clutch jaws 107 and 110 at the trimming station, as will be later described.

The embodied form of mechanism for rotating the cast plate upon the saddle 105 past the trimmers 118 and 119, (which trimmers are fixed upon and rotated by shaft 6), and cooperating with the mechanism just described, comprises a substan-

tially hemi-cylindrical shell 120, corresponding approximately in diameter to and being concentric with saddle 105. Shell 120 has an internal supporting web 121, or a plurality thereof, and a partial head 122,

which are integral with or fixed to a sleeve 123, which sleeve is loosely journaled on the cylindrical exterior of the sleeve 80. Keyed to the exterior of sleeve 123 is a worm wheel or gear wheel 124, with which meshes a worm or gear 125 on a shaft 126, journaled at 127

and 128 in the machine frame. As embodied shaft 126 is driven from shaft 6, by means of a worm 129 fixed on shaft 6, and meshing with a worm wheel 130 on shaft 126. Wheel 130 is provided with a clutch jaw 131, the worm wheel 130 being loose on shaft 126.

Fixed to rotate with shaft 126, but longitudinally slideable therealong, is a clutch member 132, which is provided with an annular collared groove 133. A yoke 134 straddles clutch member 132, and has fingers or rollers projecting into groove 133 to move the clutch member 132 into and out of engaging position. Yoke 134 is carried on an arm 135, fixed on a shaft 136, journaled at 137 and 138 in the machine frame. Fixed to shaft 136 is a hand lever 139.

Means are provided for controlling and stopping the rotation of, and for positioning the trimming mechanism, and as embodied, there is fixed to shaft 136 an arm 142, and pivotally connected to arm 142 is a rod 143 mounted to slide longitudinally in the machine frame. Pivotally connected to the opposite end of rod 143 is a detent lever 144, which is pivotally mounted at 145 upon the machine frame. The upper end of lever 144 is adapted to engage with a detent notch 146 in an annular guideway 147, formed on an extension of the worm wheel or gear wheel 124. A spring 148 is coiled about rod 143 in compression between the machine frame and a collar 149 fixed on rod 143. The spring 148 thus impels detent lever 144 into engaging position with its notch 146.

The embodied form of means for disengaging the saddle 105 from shaft 44 for separate rotation from the shaft during the trimming of the plate, as already referred to, consists of a stop 150 fixed on the shell 120, whereby carrier 105 is unclutched from shaft 44 and rests on shell 120.

The embodied form of means for taking the cast plate on to the saddle 105 and for retaining it thereon during the trimming operation comprises a rod or stop 155 formed along the edge of the saddle 105 which serves to take the plate on to the saddle during the rotation thereof at the plate casting machine. To hold the cast plate upon the saddle 105 during the trimming operation, straps 156 and 157 of semi-circular form are provided, pivotally or otherwise connected at one end to the shell 120. They are provided at the opposite end with means for raising them to admit the plate and for then drawing them down upon the plate to hold it in position during the rotation of the mechanism. Said means are preferably automatically operated, and as shown the ends of the straps 156 and 157 are connected, respectively, to arms 158 and 159, fixed to a shaft 160. Shaft 160 is journaled in bearings 161 and 162 upon the shell 120, and also

in the interior of gear wheel 124. On the exterior side of gear wheel 124 there is fixed to shaft 160 a box cam 164, which serves to oscillate the shaft at the beginning of the rotation of the mechanism to fasten the straps 156 and 157 over the plate, and at the end of the rotation to oscillate shaft 160 to raise the straps free from the trimmed plate preparatory to the removal of the plate from the saddle 105. Pins 165 and 166 fixed on the frame operate box cam 164, that is, when wheel 124 rotates, one of the pins enters the cam groove, and the inclination of the cam is such, that in passing the pin it is correspondingly rocked and thereby oscillates shaft 160. On the reverse movement of the wheel 124, the cam 164 is rocked in the opposite direction and oscillates shaft 160 in the opposite direction.

The manner of operation of the mechanism just described will be clear from the foregoing, and will be summarized but briefly as follows:—

When shaft 44 is at the right hand end of its travel in Figs. 1 and 3 and 13, clutch jaws 107 and 110 are disengaged, and saddle 105 is held in position by the shell 120. As shaft 44 begins its longitudinal movement toward the left, clutch jaws 107 and 110 engage, and saddle 105 is thereby held in fixed relation angularly with respect to shaft 44 so as to rotate therewith. Saddle 105 is carried by shaft 44 above the drag 170 of the casting machine. The casting machine shown in Fig. 8, is of the form illustrated, described and claimed in co-pending application Ser. No. 408,203, filed September 4, 1920, but it will be understood that the invention may be used with other casting machines.

In this casting machine the drag 170, after the casting operation, is brought to horizontal position with the concave side upward in position to cooperate with the machine of the present invention. In Fig. 8 and Fig. 9 the saddle 105 is shown above the plate 171, which is resting in the drag 170. The saddle 105 is then rotated in the manner and by the mechanism previously described herein. Various stages or positions of the saddle 105 are indicated diagrammatically in Figs. 9, 10, 11 and 12, the direction of movement of the parts being indicated by the arrows. In Fig. 10 the bar 155 is shown engaging the plate, in Fig. 11 the plate is shown partly removed by the rotation of the saddle 105, the bar 155 carrying the plate with the saddle. In Fig. 12 the saddle is shown back in the position of Figs. 8 and 9, but with the plate 171 supported thereon.

Rod 44 then travels to the right without rotation until saddle 105 is in position at the trimming station above the shell 120. Stop 150 now engages the saddle 105, and clutch jaws 107 and 110 are disengaged against the

pressure of spring 111, and saddle 105 is free to rotate about shaft 44 to rotate the plate past the trimming saws.

The trimming mechanism is brought into 5 operation by throwing the hand lever 139, which throws in clutch member 131 and 132 and starts shaft 126 into rotation. Straps 156 and 157 fasten plate 171 on the saddle in the manner already described.

10 When hand lever 139 is operated, it rocks shaft 136 to throw in the clutch 131, 132 as just described, and through arm 142 and rod 143, detent lever 144 is thrown out of notch 146. Gear wheel 124 is then rotated 15 through its drive 125 from shaft 126, and this, through sleeve 123 and the connections already described, rotates shell 120 and saddle 105, carrying the plate 171 past the rotating trimmers 118 and 119 to trim the 20 plate. At the end of the revolution detent lever 144 engages notch 146 on gear 124 and brings the mechanism to rest. The movement of the lever into the notch permits 25 spring 148 to throw out the clutch 131, 132, and the mechanism stops. Straps 156 and 157 had been released by the mechanism already described.

The invention in its broader aspects is not limited to the details of construction herein 30 shown and described, but changes may be made therein within the scope of the accompanying claims without departing from the principles of the invention and without sacrificing its chief advantages.

35 What I claim is:—

1. A machine for operating upon stereotyped plates including in combination means for casting a plate including a drag, a trimming mechanism, a plate carrier movable to 40 and fro between the casting means and trimming mechanism, means for taking the plate from the drag on to the carrier, and means for effecting relative movement of the carrier and trimming mechanism to trim the 45 plate.

2. A machine for operating upon stereotyped plates including in combination a plate carrier movable to and fro between a source of plate supply and a trimming mechanism, 50 means for rotating the carrier at the source of supply to take a plate on to the carrier, and means for effecting relative movement of the carrier and trimming mechanism to trim the plate.

3. A machine for operating upon stereotyped plates including in combination a plate carrier movable to and fro between a source of plate supply and a trimming mechanism, means for rotating the carrier 60 at the source of supply to take a plate on to the carrier, and means for rotating the plate carrier at the trimming mechanism to trim the plate.

4. A machine for operating upon stereotyped plates including in combination a 65

plate carrier movable to and fro between a source of plate supply and a trimming mechanism, means for rotating the carrier at the source of supply to engage the concave side of and to take a plate on to the carrier, and means for effecting relative movement of the carrier and trimming mechanism to trim the plate.

5. A machine for operating upon stereotyped plates including in combination a 75 plate carrier movable to and fro between a source of plate supply and a trimming mechanism, means for rotating the carrier at the source of supply to engage the concave side of and to take a plate on to the carrier, and means for rotating the plate carrier at the trimming mechanism to trim the plate.

6. A machine for operating upon stereotyped plates including in combination a 85 cylindrically shaped plate carrier movable to and fro between a source of plate supply and a trimming mechanism, means for rotating the carrier at the source of supply to take a plate on to the carrier, and means for 90 effecting relative movement of the carrier and trimming mechanism to trim the plate.

7. A machine for operating upon stereotyped plates including in combination a 95 cylindrically shaped plate carrier movable to and fro between a source of plate supply and a trimming mechanism, means for rotating the carrier at the source of supply to take a plate on to the carrier, and means for 100 rotating the plate carrier at the trimming mechanism to trim the plate.

8. A machine for operating upon stereotyped plates including in combination a cylindrically shaped plate carrier movable to and fro between a source of plate supply 105 and a trimming mechanism, means for rotating the carrier at the source of supply to engage the concave side of and to take a plate on to the carrier, and means for effecting relative movement of the carrier 110 and trimming mechanism to trim the plate.

9. A machine for operating upon stereotyped plates including in combination a cylindrically shaped plate carrier movable 115 to and fro between a source of plate supply and a trimming mechanism, means for rotating the carrier at the source of supply to engage the concave side of and to take a plate on to the carrier, and means for rotating the plate carrier at the trimming mechanism to trim the plate.

10. A machine for operating upon stereotyped plates including in combination a 125 cylindrically shaped carrier movable to and fro between a source of supply and a trimming station and adapted to pass within the concave side of and to take a plate at the source of supply, trimming means, and means for effecting relative movement be- 130

tween the carrier and trimming means to trim the plate.

11. A machine for operating upon stereotype plates including in combination a shaft and a plate carrier supported thereon, a source of plate supply, a trimming mechanism, means for moving the shaft longitudinally to move the carrier to and fro between the source of supply and the trimming mechanism, and means rotating upon the shaft to further operate upon the plate.

12. A machine for operating upon stereotype plates including in combination a shaft and a plate carrier supported thereon, a source of plate supply, a trimming mechanism, means for moving the shaft longitudinally to move the carrier to and fro between the source of supply and the trimming mechanism, and means rotating upon the shaft while it is at rest longitudinally to further operate upon the plate.

13. A machine for operating upon stereotype plates including in combination a shaft and a plate carrier supported thereon, a source of plate supply, a trimming mechanism, means for moving the shaft longitudinally to move the carrier to and fro between the source of supply and the trimming mechanism, and means rotating upon the shaft while the plate carrier is at the trimming mechanism.

14. A machine for operating upon stereotype plates including in combination a shaft and a plate carrier supported thereon, a source of plate supply, a trimming mechanism, means for moving the shaft longitudinally to move the carrier to and fro between the source of supply and the trimming mechanism, and means for rotating the shaft while the plate carrier is at the source of supply.

15. A machine for operating upon stereotype plates including in combination a shaft and a plate carrier supported thereon, a source of plate supply, a trimming mechanism, means for moving the shaft longitudinally to move the carrier to and fro between the source of supply and the trimming mechanism, and means rotating upon the shaft while it is longitudinally at rest and while the plate carrier is at the trimming mechanism.

16. A machine for operating upon stereotype plates including in combination a shaft and a plate carrier supported thereon, a source of plate supply, a trimming mechanism, means for moving the shaft longitudinally to move the carrier to and fro between the source of supply and the trimming mechanism, and means for rotating the shaft while it is longitudinally at rest and while the plate carrier is at the source of supply.

17. A machine for operating upon stereotype plates including in combination a shaft and a cylindrically shaped plate carrier sup-

ported thereon, a source of plate supply, a trimming mechanism, means for moving the shaft longitudinally to move the carrier to and fro between the source of supply and the trimming mechanism.

18. A machine for operating upon stereotype plates including in combination a shaft and a cylindrically shaped plate carrier supported thereon, a source of plate supply, a trimming mechanism, means for moving the shaft longitudinally to move the carrier to and fro between the source of supply and the trimming mechanism, and means rotating upon the shaft to further operate upon the plate.

19. A machine for operating upon stereotype plates including in combination a shaft and a cylindrically shaped plate carrier supported thereon, a source of plate supply, a trimming mechanism, means for moving the shaft longitudinally to move the carrier to and fro between the source of supply and the trimming mechanism, and means rotating upon the shaft while it is at rest longitudinally to further operate upon the plate.

20. A machine for operating upon stereotype plates including in combination a shaft and a cylindrically shaped plate carrier supported thereon, a source of plate supply, a trimming mechanism, means for moving the shaft longitudinally to move the carrier to and fro between the source of supply and the trimming mechanism, and means rotating upon the shaft while the plate carrier is at the trimming mechanism.

21. A machine for operating upon stereotype plates including in combination a shaft and a plate carrier supported thereon, a source of plate supply, a trimming mechanism, means for moving the shaft longitudinally to move the carrier to and fro between the source of supply and the trimming mechanism, and means for rotating the plate carrier independently of the shaft.

22. A machine for operating upon stereotype plates including in combination a shaft and a plate carrier supported thereon, a source of plate supply, a trimming mechanism, means for moving the shaft longitudinally to move the carrier to and fro between the source of supply and the trimming mechanism, and devices for rotating the shaft and plate carrier together or one independently of the other.

23. A machine for operating upon stereotype plates including in combination a shaft and a plate carrier supported thereon, a source of plate supply, a trimming mechanism, means for moving the shaft longitudinally to move the carrier to and fro between the source of supply and the trimming mechanism, and means for rotating the plate carrier and shaft together at one end of the longitudinal travel thereof.

24. A machine for operating upon stereo-

- type plates including in combination a shaft and a plate carrier supported thereon, a source of plate supply, a trimming mechanism, means for moving the shaft longitudinally to move the carrier to and fro between the source of supply and the trimming mechanism, and means for effecting relative rotation between the plate carrier and shaft at one end of the longitudinal travel thereof.
- 10 25. A machine for operating upon stereotype plates including in combination a shaft and a plate carrier supported thereon, a source of plate supply, a trimming mechanism, means for moving the shaft longitudinally to move the carrier to and fro between the source of supply and the trimming mechanism, and means for rotating the shaft and plate carrier together in taking a plate at the source of supply.
- 15 26. A machine for operating upon stereotype plates including in combination a shaft and a plate carrier supported thereon, a source of plate supply, a trimming mechanism, means for moving the shaft longitudinally to move the carrier to and fro between the source of supply and the trimming mechanism, and means for effecting relative movement of the shaft and plate carrier at the trimming mechanism.
- 20 27. A machine for operating upon stereotype plates including in combination a shaft and a plate carrier supported thereon, a source of plate supply, a trimming mechanism, means for moving the shaft longitudinally to move the carrier to and fro between the source of supply and the trimming mechanism, and means for rotating the plate carrier relatively to the shaft at the trimming mechanism.
- 25 28. A machine for operating upon stereotype plates including in combination a shaft and a plate carrier supported thereon, a source of plate supply, a trimming mechanism, means for moving the shaft longitudinally to move the carrier to and fro between the source of supply and the trimming mechanism, means for disengaging the plate carrier from the shaft at the trimming station and for rotating the plate carrier to trim the plates.
- 30 29. A machine for operating upon stereotype plates including in combination a shaft and a plate carrier thereon longitudinally movable to and fro between two plate stations, means operating automatically to reverse the travel thereof at one of said stations.
- 35 30. A machine for operating upon stereotype plates including in combination a shaft and a plate carrier thereon longitudinally movable to and fro between two plate stations, hand operated means for starting said longitudinal movement, means operating automatically to reverse the travel thereof at one of said stations.
- 40 31. A machine for operating upon stereotype plates including in combination a shaft and a plate carrier thereon, attachable and detachable from the shaft, and longitudinally movable to and fro between two plate stations, and means operating automatically to reverse the travel thereof at one of said stations.
- 45 32. A machine for operating upon stereotype plates including in combination a shaft and a plate carrier thereon longitudinally movable to and fro between two plate stations, means operating automatically to reverse the travel thereof at one of said stations, and means for effecting rotation of said shaft at the point of reversal of the longitudinal movement.
- 50 33. A machine for operating upon stereotype plates including in combination a shaft and a plate carrier thereon longitudinally movable to and fro between two plate stations, means operating automatically to reverse the travel thereof at one of said stations, and means for rotating the plate carrier independently of the shaft at one end of their longitudinal travel.
- 55 34. A machine for operating upon stereotype plates including in combination a shaft and a plate carrier thereon longitudinally movable to and fro between two plate stations, means operating automatically to reverse the travel thereof at one of said stations, and means for rotating the plate carrier independently of the shaft at the other of said stations.
- 60 35. A machine for operating upon stereotype plates including in combination a plate carrier movable to and fro between a source of plate supply and a trimming mechanism, means for taking a plate upon the carrier at the source of supply, and means called into action by the operative for effecting relative movement of the carrier and trimming mechanism to trim the plate.
- 65 36. A machine for operating upon stereotype plates including in combination a plate carrier movable to and fro between a source of plate supply and a trimming mechanism, automatically operating means for taking a plate upon the carrier at the source of supply, and means called into action by the operative for effecting relative movement of the carrier and trimming mechanism to trim the plate.
- 70 37. A machine for operating upon stereotype plates including in combination means for casting a plate, a trimming mechanism, a plate carrier movable to and fro between the casting means and trimming mechanism, means for taking the plate from the casting means on to the carrier, and means called into action by the operative for effecting relative movement of the carrier and trimming mechanism to trim the plate.
- 75 38. A machine for operating upon stereo-

- type plates including in combination means for casting a plate, a trimming mechanism, a plate carrier movable to and fro between the casting means and trimming mechanism, automatically operating means for taking the plate from the casting means on to the carrier, and means called into action by the operative for effecting relative movement of the carrier and trimming mechanism to trim the plate. 5
39. A machine for operating upon stereotype plates including in combination a plate carrier movable to and fro between a source of plate supply and a trimming mechanism, automatically operating means for rotating the carrier at the source of supply to take a plate on to the carrier, and means for effecting relative movement of the carrier and trimming mechanism to trim the plate. 15
- 20 40. A machine for operating upon stereotype plates including in combination a plate carrier movable to and fro between a source of plate supply and a trimming mechanism, means for rotating the carrier at the source 25 of supply to take a plate on to the carrier, and means called into action by the operative for effecting relative movement of the carrier and trimming mechanism to trim the plate. 30
41. A machine for operating upon stereotype plates including in combination a plate carrier movable to and fro between a source of plate supply and a trimming mechanism, means for rotating the carrier at the source 35 of supply to take a plate on to the carrier, and means called into action by the operative for rotating the plate carrier at the trimming mechanism to trim the plate. 35
42. A machine for operating upon stereotype plates including in combination a shaft 40 and a plate carrier supported thereon, a source of plate supply, a trimming mechanism, means for moving the shaft longitudinally to move the carrier to and fro between the source of supply and the trimming mechanism, and means called into action by the operative for rotating the plate carrier at the trimming station. 45
43. A machine for operating upon stereotype plates including in combination a shaft 50 and a plate carrier supported thereon, a source of plate supply, a trimming mechanism, means for moving the shaft longitudinally to move the carrier to and fro between the source of supply and the trimming mechanism, and means called into action by the operative for rotating the plate carrier at the trimming station. 55
44. A machine for operating upon stereotype plates including in combination a shaft 55 and a plate carrier supported thereon, a source of plate supply, a trimming mechanism, means for moving the shaft longitudinally to move the carrier to and fro between the source of supply and the trimming mechanism, and means called into action by the operative for rotating the plate carrier to trim the plate. 60
45. A machine for operating upon stereotype plates including in combination a shaft 70 and a plate carrier supported thereon, a source of plate supply, a trimming mechanism, means for moving the shaft longitudinally to move the carrier to and fro between the source of supply and the trimming mechanism, and means called into action by the operative for rotating the plate carrier independently of the shaft. 75
46. A machine for operating upon stereotype plates including in combination a shaft 80 and a plate carrier supported thereon, a source of plate supply, a trimming mechanism, means for moving the shaft longitudinally to move the carrier to and fro between the source of supply and the trimming mechanism, and devices for rotating the shaft and plate carrier together or one independently of the other, one of said devices operating automatically and the other being called into action by the operative. 85
47. A machine for operating upon stereotype plates including in combination a shaft 90 and a plate carrier supported thereon, a source of plate supply, a trimming mechanism, means for moving the shaft longitudinally to move the carrier to and fro between the source of supply and the trimming mechanism, and devices operating automatically and manually for rotating the shaft and 100 plate carrier together or one independently of the other. 95
48. A machine for operating upon stereotype plates including in combination a shaft 105 and a plate carrier supported thereon, a source of plate supply, a trimming mechanism, means for moving the shaft longitudinally to move the carrier to and fro between the source of supply and the trimming mechanism, and means called into action by the 110 operative for rotating the plate carrier relatively to the shaft at the trimming mechanism. 110
49. A machine for operating upon stereotype plates including in combination a shaft 115 and a plate carrier supported thereon, a source of plate supply, a trimming mechanism, means for moving the shaft longitudinally to move the carrier to and fro between the source of supply and the trimming mechanism, and means called into action by the 120 operative for disengaging the plate carrier from the shaft at the trimming station and means called into action by the operative for rotating the plate carrier to trim the plate. 125
50. A machine for operating upon stereotype plates including in combination a plate carrier movable to and fro between a source of plate supply and a trimming mechanism, means engaging the concave side of a plate 130

and thereby taking it upon the carrier at the source of supply, and means for effecting relative movement of the carrier and trimming mechanism to trim the plate.

- 5 51. A machine for operating upon stereotype plates including in combination means for casting a plate, a trimming mechanism, a plate carrier movable to and fro between the casting means and trimming mechanism, 10 means rotatable to take the plate from the casting means on to the carrier, and means for effecting relative movement of the carrier and trimming mechanism to trim the plate.
- 10 52. A machine for operating upon stereo-

type plates including in combination a carrier movable to and fro between a source of supply and a trimming station and adapted to pass within the concave side of and to take a plate at the source of supply, trimming means, and means for effecting relative movement between the carrier and trimming means to trim the plate. 20

In testimony whereof, I have signed my name to this specification, in the presence 25 of two subscribing witnesses.

ALBERT A. HENZI.
